CLAIM

USPC **D6/356**

The ornamental design for a seat for a motor vehicle, as shown and described.

(58) **Field of Classification Search**

DESCRIPTION

USPC D6/333, 334, 344, 348, 356, 360-366,

FIG. 1 is a front left perspective view for a seat for a motor vehicle, showing our new design;

D6/368, 369-371, 374, 377, 380, 381,

FIG. 2 is a rear right perspective view thereof;

D6/708, 716; D12/52; D11/184;

FIG. 3 is a front view thereof;

D21/521, 534-539, 674, 676, 687, 688,

FIG. 4 is a rear view thereof;

D21/690, 828; D23/292; D30/118

FIG. 5 is a right side view thereof;

CPC ... B64D 11/06; B64D 11/064; B64D 11/0601;

(Continued)

B64D 11/0602; B64D 11/0606; B64D

11/0604; B64D 11/0605; B64D 11/0641;

B64D 11/0638; B64D 11/0643; B64D
